JOHN CULLEN ROBERTSON, OF ANNAPOLIS, MARYLAND, ASSIGNOR TO LOCKE INSULATOR CORPORATION, OF BALTIMORE, MARYLAND, A CORPORATION OF MARYLAND.

INSULATOR-ASSEMBLING JIG.

Application filed July 14, 1927. Serial No. 205,830.

The invention relates to apparatus used in the assembling of multi-part insulators and has special reference to means for assembling insulators of the type embodying a plurality of porcelain shells adapted and intended to be secured in nested relation.

The principal object of the invention, generally considered, is to provide means for centering insulator shells while they are being secured together by means of cement applied in the usual manner as for instance by squirting it about and into the crevices at the joints.

It is well known that when the porcelain shells are dried and fired during the course of their manufacture they frequently warp and become out of round so that their assembly into a unit becomes more or less difficult from the viewpoint of accuracy. It is desirable that the shells be nested in coaxial relation so as to avoid the bringing of any unequal strains upon different portions when in service. The usual method is to mount the lowermost shell upon a support and then nest the series of shells with respect to said lowermost shell and to one another, with wooden wedges or blocks interposed between the successive shells for the purpose of maintaining them in the proper relation to one another while the cement is squirted and then afterwards permitted to set, the blocks or wedges remaining in place for a considerable period of time, that is for as long as necessary to effect setting and hardening of the cement. This requires hand work and is not accurate inasmuch as reliance is placed upon the trueness of the eye of the operator who generally simply squints at the assembly from different angles to ascertain when the shells are in alinement or coaxial relation. There is another objection to the usual method and that is in case the blocks drop out or are disturbed one or more of the shells may be thrown out of line with respect to the others, necessitating resetting, if the cement is still plastic or discarding the assembly if the cement has set and hardened. Furthermore, a large number of such blocks or wedges are needed to effect the assembling of an ordinary day's output of units.

It is with all of the above facts in view that I have designed the present invention which has for an important object the provision of a pedally and manually operable machine for the purpose of alining a plurality of shells and holding them in axial relation and under a desired pressure while and, possibly, after the cement has been squirted in.

Another important object of the invention is to provide a device for this purpose in which one centering means is spring pressed so as to yield in accordance with variations in the degree of extension of one shell beyond another, the various centering means being therefore relatively movable to compensate for manufacturing variations in the same design of unit or variations in different designs, means being also provided whereby the centering means may be adjusted to meet different conditions and in accordance with differences in the diameters of the shells.

A further object of the invention is to provide a machine of this character provided with latch means whereby the parts may be held rigid so that pressure on the assembly may be maintained and any possible displacement of the parts prevented.

A further object is to provide a manually operable latch means cooperating with a plunger element so as to be readily releasable therefrom to permit disconnection of the centering means from the assembly.

Still another object is to provide a machine of this character in which the moving parts may be counterbalanced so as to decrease the labor involved in moving them from one position to another.

An additional object is the provision of a machine of this character which will be simple and inexpensive to manufacture, easy to set up and operate as well as adjust, positive in action, efficient and durable in service, and a general improvement in the art.

To the attainment of the foregoing and other objects and advantages, the invention preferably consists in the details of construction and the arrangement and combination of parts to be hereinafter more fully described and claimed, and illustrated in the accompanying drawing in which:

Figure 1 is a side elevation of the machine showing the moving parts latched down in operative position.

Figure 2 is a detail section taken through the manually releasable stop device,

Figure 3 is a detail cross section taken on the line 3—3 of Figure 1, and

Figure 4 is a side elevation of the centering members detached from the remainder of the machine.

Referring more particularly to the drawing I have shown the device as comprising a suitable support indicated generally at 1, this support being capable of being constructed in any desired manner, and suitable material and of any preferred size. Mounted on this support, which may conveniently be of table or bench-like form, is a frame structure designated as a whole by the numeral 2 and including a platform or base portion 3, an upright or standard 4 and vertically aligned bearing members 5 at the top of the latter. I have also shown an upstanding support 6 suitably mounted on the standard 4 and having connected therewith an arm 7 strengthened by an inclined brace 8 secured thereto and to the upright or standard 4. Grooved pulleys or rollers 9 and 10 are preferably journaled upon the arm 7 at the upper and lower ends thereof and serve as guide means for a chain 11, or other flexible member, carrying a weight 12 and connected at 13 with a plunger 14 slidable through the bearings 5, this plunger carrying the centering means indicated as a whole at 15 and to be described in detail hereinafter. The purpose of the pulley, flexible member and weight construction is simply to counterbalance the weight of the plunger 14, centering means and other moving parts to be described so that movement thereof will be facilitated.

Suitably mounted and preferably rotatable upon the base or platform portion 3 of the frame structure 2 is a preferably disk-like supporting member 16 having means 17 thereon for guidably receiving the reduced portion 18 of an insulator shell 19, and this member 16 is located coaxially with respect to the plunger 14. The insulator here disclosed is represented as including not only the shell or section 19 but other sections or shells 20, 21 and 22, the last named being the endmost. It will be understood that, as shown, all these shells are in inverted position as compared with their normal position when in service. All the sections are of such construction that they must be nested to be assembled.

The centering device is here disclosed as comprising a hub member 23 adjustably mounted along the plunger 14 and adapted to be secured in a selected position as by means of set screws 24 or the like. Radiating from this hub member are arms 25, pref-

erably three in number, these arms carrying depending fingers 26 having angularly extending and preferably inwardly directed end portions 27 of hook-like form adapted to engage within the open end of the shell 21. The degree of extension of these fingers 26 with respect to the arms 25 is intended to be variable and for this reason the fingers are represented as threaded where they pass through the arms and equipped with nuts 28 bearing against opposite sides of the arms. In order that the device may be used satisfactorily in connection with shells of different diameters the arms 25 are preferably formed with elongated slots 29 through 75 which the fingers pass, it being evident that the fingers may therefore be moved radially with respect to the plunger and secured in such adjusted position.

The centering device further includes a 85 preferably tapered plug-like member 30 slideable on the plunger and adapted to fit within the open end of the shell or section 22, this member having an outstanding flange 31 adapted to engage upon the edge of the shell 90 to prevent it from slipping in to an excessive extent. The member 30 is urged downwardly as by a coil spring 32 surrounding the plunger and having one end abutting against the member 30 and its other end abutting 95 against an adjustable stop collar 33 held as by a set screw 34. In view of this construction it will be seen that the member 30 is movable toward the hub 23 and may have its position varied with respect to the hook-like ends 27 of the fingers so as to function properly even though there is a considerable variation in the extent of projection of the shell 22 beyond the shell 21. The lower end of the plunger is preferably tapered at 100 105 so as to correspond substantially to the usual insulator pin, not shown, this end of course engaging within the pin receiving socket when the insulator parts are being assembled.

In order that the centering means may be brought into operative engagement with the various shells during the assembling operation, I preferably provide a foot operated mechanism for effecting the necessary movement, this means including a treadle 36 pivoted at 37 upon the support 1 and pivotally connected with a link 38 in turn pivoted at 39 to the inner end of a lever 40 pivoted intermediate its ends upon the support 1. A reach rod 41 is pivotally connected with the other end of the lever 40 and with an intermediate point 42 in the length of a lever 43 located above the frame 2 and pivoted at 44 in some suitable manner as for example upon the brace 8. The lever 43 may be 115 forked or may have an opening therein for the passage of the plunger 14 and this lever carries means to be described adapted to engage against a stop collar 45 adjustably mounted upon the plunger and held as by 120 125 130

a set screw 46. The lever 43 is intended to be capable of manual operation for which reason it is disclosed as terminating in a handle 47. The operative connection between the lever and the stop 45 is here represented as including a latch plate 48 slidably mounted on the underside of the lever 43 and guided in its movement longitudinally thereof as by means of screws 49 or 10 the like passing through slots 50 in the latch plate and threaded into tapped holes in the lever. Obviously, any equivalent guide means may be provided within the scope of the invention. The latch plate is here 15 shown as having a guide plunger 51 at its outer end slidable through the handle 47 and through a stop bracket 52 carried by the lever, the plunger 51 carrying an abutment washer or other similar element 53 engaging 20 a coil spring 54 surrounding the plunger and confined between the washer and the bracket 52, this spring acting normally to urge the latch plate into engagement with the plunger at a point immediately above the stop collar 45 and in engagement with the latter. When the treadle 36 is in fully de- 25 pressed position with the centering means in engagement with the insulator sections to be assembled it is highly desirable that it be maintained in such position without re- 30 quiring constant pressure from the foot of the operator and for this reason I have pro- 35 vided holding means which may conveniently consist of a latch 55 pivoted at 56 upon the support 1 and adapted to be swung over and into engagement with the treadle as indicated in Figure 1.

In the operation, it is of course apparent that originally or initially the treadle 36 is in its uppermost position, the lever 43 being 40 also in its uppermost position so that the plunger 14 will be elevated with the centering means 15 out of the way so that the operator may place the series of shells in nested relation and in position upon the member 16. The operator then either grasps the lever 43 and pulls it down or presses upon the treadle 36 to force it down, in either case 45 the result being that the engagement of the latch plate 48 with the stop 45 will force the plunger 14 and centering means downwardly. When this occurs the tapered plug-like member 30 will engage within the open end of the section or shell 22, the spring 50 55 32 being compressed as the plunger continues its downward movement. The movement is continued until the hooked ends 27 of the fingers 26 engage within the open end of the shell or section 21. The lowermost 60 section 19 is held in proper position and in axial relation to the plunger by means of the guides 17 carried by the member 16. The member 30 centers the shell or section 22 and the fingers 26 center the shell 21. 65 It may safely be assumed that the shell or

section 20 will adjust or center itself inasmuch as it is confined between the two properly centered shells 19 and 21. After the downward movement of the centering means has been completed, the latch 55 may be 70 swung over the treadle 36 to maintain the parts stationary, all the insulator shell sections being consequently held in the proper assembled relation with pressure applied thereto. Cement for permanently securing 75 the shell sections together is then introduced within or between the shells, the usual method being by means of a squirt gun similar to the grease guns used for applying lubricant to motor vehicles and the like. 80 Details in this respect are unnecessary as they form no part of the present invention. As the member 16 is rotatable upon the base or platform 3 it is apparent that the entire assembly may be rotated by hand before, 85 during or after the operation of injecting the cement and in this way it is apparent that the operator may readily have access to the parts for insuring a uniform and proper distribution of the necessary quantity of cement. If preferred the pressure upon the treadle may not be made complete until after the cement has been injected in place and furthermore, if desired, if the treadle is not latched down, the operator 90 may alternately apply and relieve the pressure on the treadle so as to jolt the assembly more or less rapidly and thereby cause the cement to settle in the cavities and about the stems of the successive shells, air bubbles 95 being thus forced out so that the cement will 100 be of uniform mass and solidity. A few moments may be permitted to elapse for the cement to start its hardening if preferred, though as a matter of fact the pressure upon the treadle may then be released and the lever 43 swung upwardly to remove the centering means from engagement with the assembly, the entire assembly being then lifted off and out of the machine and set aside so 105 that the cement will then set thoroughly and dry. Obviously, the pin, not shown, may be cemented in place before or after the assembly is removed from the machine, this detail being immaterial. 110

From the foregoing description and a study of the drawing it will be apparent that I have thus provided a simply constructed, inexpensive and very easily operated machine by means of which the labor 115 in assembling will be reduced and the work greatly expedited. In addition to the saving in time and labor the machine has the great advantage of insuring accuracy as the various shell sections are centered automatically instead of reliance being placed upon the eye of the operator. Canted assemblies are practically an impossibility in the use of this apparatus unless of course an attempt is made to assemble sections which 120 125 130

are so seriously warped or out of round as to be unfit for use. It is really believed that the construction, operation and advantages will be readily apparent to one skilled in the art without further explanation.

While I have shown and described a preferred embodiment of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the scope of the claims hereunto appended.

Having thus described the invention, I claim:

1. In an insulator assembling jig, the combination of a support, means on the support for supporting a plurality of insulator sections in nested relation, means for applying pressure upon the insulator sections axially thereof, and means for centering the sections with respect to one another.
2. In an insulator assembling jig, a supporting structure, means carried thereby for supporting a series of nested insulator sections, a plunger movably mounted coaxially of said assembled sections, and means carried by the plunger and engageable with certain of the sections for centering the same with respect to one another and to the supporting means.
3. In an insulator assembling jig, a supporting structure, means carried thereby for supporting a series of nested insulator sections, a plunger movably mounted coaxially of said assembled sections, and means carried by the plunger and engageable with certain of the sections for centering the same with respect to one another and to the supporting means, said centering means including an element engageable within one endmost section and further including fingers engageable within the next adjacent section.
4. In an insulator assembling jig, a supporting structure, means carried thereby for supporting a series of nested insulator sections, a plunger movably mounted coaxially of said assembled sections, and means carried by the plunger and engageable with certain of the sections for centering the same with respect to one another and to the supporting means, said centering means including an element engageable within one endmost section and further including fingers engageable within the next adjacent section, said fingers being radially adjustable with respect to the plunger.
5. In an insulator assembling jig, a supporting structure, means carried thereby for supporting a series of nested insulator sections, a plunger movably mounted coaxially of said assembled sections, and means carried

by the plunger and engageable with certain of the sections for centering the same with respect to one another and to the supporting means, said centering means including an element engageable within one endmost section and further including fingers engageable within the next adjacent section, said fingers being radially adjustable with respect to the plunger and terminating in inwardly directed hook-like extensions.

6. In a machine of the character described, a support, means mounted on the support for supporting a plurality of insulator sections arranged in nested relation, a plunger mounted above and longitudinally movable in coaxial relation to the sections, centering means carried by the plunger and engageable with the sections, and means for applying downward pressure upon the plunger.

7. In a machine of the character described, a support, means mounted on the support for supporting a plurality of insulator sections arranged in nested relation, a plunger mounted above and longitudinally movable in coaxial relation to the sections, centering means carried by the plunger and engageable with the sections, and pedal operated means connected with the plunger for moving the same downwardly.

8. In a machine of the character described, a support, means mounted on the support for supporting a plurality of insulator sections arranged in nested relation, a plunger mounted above and longitudinally movable in coaxial relation to the sections, centering means carried by the plunger and engageable with the sections, lever means engageable with the plunger, and pedal operated means connected with the lever for moving the same downwardly.

9. In a machine of the character described, a supporting structure, means on said structure for supporting a plurality of insulator sections arranged in nested relation, a plunger longitudinally movably mounted in the supporting structure in coaxial relation to the insulator sections, centering means on the plunger engageable with the insulator sections, a pivoted lever having a releasable latch connection with the plunger, and foot operated means for moving said lever downwardly.

10. In a machine of the character described, a supporting structure, means on said structure for supporting a plurality of insulator sections arranged in nested relation, a plunger longitudinally movably mounted in the supporting structure in coaxial relation to the insulator sections, centering means on the plunger engageable with the insulator sections, a pivoted lever having a releasable latch connection with the plunger, foot operated means for moving said lever downwardly, and counterbalanc-

ing means for the plunger and centering means carried thereby.

11. In a machine of the character described, a supporting structure, means on said structure for supporting a plurality of insulator sections arranged in nested relation, a plunger longitudinally movably mounted in the supporting structure in coaxial relation to the insulator sections, centering means on the plunger engageable with the insulator sections, a pivoted lever having a releasable latch connection with the plunger, foot operated means for moving said lever downwardly, counterbalancing means for the plunger and centering means carried thereby, and spring means normally urging the lever upwardly.
12. In a machine of the character described, a supporting structure, means rotatable thereon for supporting a plurality of insulator sections in nested relation, a plunger slideable and rotatable in the supporting structure in coaxial relation to said sections, centering means carried by the plunger, and means for moving the plunger vertically.

13. In a machine of the character described, a supporting structure, means rotatable thereon for supporting a plurality of insulator sections in nested relation, a plunger slideable and rotatable in the supporting structure in coaxial relation to said sections, centering means carried by the plunger, means for moving the plunger vertically including a pivoted manually movable arm located at the upper end of the plunger, and a treadle located at the lower portion of the supporting structure and operatively connected with the lever.

14. In a machine of the character described, a supporting structure, means mounted thereon for supporting a plurality of insulator sections arranged in nested relation, a plunger vertically slidably mounted within the supporting structure and carrying centering means engageable with the insulator sections, adjustably spaced stop members on the plunger, a pivoted lever, and a grip released latching means on the lever engageable with the plunger between the stop means thereon.

15. In a machine of the character described, means for supporting a plurality of insulator sections in nested relation, a slidably mounted plunger arranged in substantially coaxial relation to the insulator sections, and centering means carried by the plunger, the centering means including a hub member, a plurality of arms radiating

therefrom, a central centering member slideable on the plunger, and a series of fingers carried by said arms and arranged outwardly of and in spaced relation to said central slideable member.

16. In a machine of the character described, means for supporting a plurality of insulator sections in nested relation, a slidably mounted plunger arranged in substantially coaxial relation to the insulator sections, and centering means carried by the plunger, the centering means including a hub member, a plurality of arms radiating therefrom, a central centering member slideable on the plunger, and a series of fingers carried by said arms and arranged outwardly of and in spaced relation to said central slideable member, said arms being slotted and said fingers being radially adjustable along the slots.

17. In a machine of the character described, means for supporting a plurality of insulator sections in nested relation, a slidably mounted plunger arranged in substantially coaxial relation to the insulator sections, and centering means carried by the plunger, the centering means including a hub member, a plurality of arms radiating therefrom, a central centering member slideable on the plunger, a series of fingers carried by said arms and arranged outwardly of and in spaced relation to said central slideable member, and means whereby said fingers may be adjusted to vary the projection thereof from said arms.

18. Means for centering a plurality of nested insulator sections, comprising means guidably receiving one endmost section, a plunger adapted to extend within the other endmost section, a spring pressed element slideable along the plunger and engageable within the second named end section, and a plurality of guide fingers carried by the plunger and engageable within an intermediate one of the sections.

19. In a machine of the character described, the combination of means for guidably supporting one endmost one of a series of insulator sections arranged in nested relation, means extendible within the other endmost section in substantially coaxial relation thereto, and a plurality of relatively movable elements engageable within certain of the sections for automatically centering the same with respect to one another.

In testimony whereof I affix my signature.

JOHN CULLEN ROBERTSON.
